TRUSS

Lewis A. Fritsch, Cincinnati, Ohio

Application July 12, 1935, Serial No. 31,125

9 Claims. (Cl. 128—95)

This invention aims to provide a novel means for retaining truss pads of different sizes, to provide novel means whereby a truss pad may be mounted for rotatable adjustment, to provide novel means whereby the truss pad may be mounted tiltably, and to provide novel means for holding the pad in any position to which it may have been tilted.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing:

Fig. 1 shows in elevation, a device constructed in accordance with the invention;

Fig. 2 is a top plan;

Fig. 3 is a top plan wherein the pad and attendant parts appear in section;

Fig. 4 is a plan of the inner washer;

Fig. 5 is a plan of the retaining disk.

The letter P marks a truss pad, which may be constructed as desired. The pad P comprises a resilient body 1, located within a flexible cover 2 secured to a base 3, which may be of leather. The base 3 projects outwardly beyond the body of the pad to form a marginal bead 4. The base 3 is provided with a central opening 23.

A metal inner washer 5 is bound between the body 1 of the pad and the base 3, the opening 6 of the washer registering with the opening 23 in the base 3. The numeral 7 designates a metal retaining disk having an offset hub 8 provided with openings 18, the hub forming a marginal flange 9 in the retaining disk 7. The flange 9 of the retaining disk 7 is bound between the inner washer 5 and the body 1 of the pad. The hub 8 extends into the opening 6 of the washer 5 to prevent the retaining disk 7 from slipping laterally.

The letter B designates a back plate, preferably made of metal and divided along a longitudinal line 10 to form parts 11 provided in their inner edges with notches forming an opening 24 in the back plate, the opening 24 of the back plate being in registration with the opening 23 of the base 3.

The parts 11 of the back plate B are supplied with an inwardly inclined lip 12 which grips the bead 4 of the pad P closely. Slits 14 may be formed in the lip 12, to facilitate the making of the lip, but this construction is not insisted upon.

Links 15 are disposed against the outer surface of the back plate B and extend across the line 10 of division of the parts 11 of the back plate, the links 15 have longitudinal slots 16, through which extend securing elements 17, threaded into the parts 11 of the back plate B, the heads of the screws engaging the links 15.

An outer retainer in the form of a washer 19, preferably of metal, rests against the outer surface of the parts 11 of the back plate and extends across the dividing line 10, the opening in the outer washer 19 being marked by the numeral 29. The outer washer 19 is bridged across by a rigid connector 20 having hook-shaped eyes 21 at its ends, the connector being long enough so that the bends of the hooks 21 can bear on the outer surface of the washer 19. Securing devices 30 such as screws, extend through the hooks 21 of the connector 20, through the opening 29 of the washer 19, through the opening 24 in the back plate, and through the opening 23 in the base 3 of the pad P. The securing devices 30 are threaded into the openings 18 of the retaining disk 7.

The intermediate portion of the connector 20 is received in an eye 22 formed at the end of a double-walled arm 25 attached by securing elements 26 to the resilient body-engaging member 27 of the truss. An adjusting device 28 is threaded into the arm 25 and bears against the back plate B, between the connector 20 and the end of the body-engaging member 27. The body-engaging member 27 generally terminates in a strap (not shown) which may be connected to the outwardly projecting portion of the adjusting device or screw 28.

By setting up the screws 30, the outer washer 19, the base 3, the body 1, the inner washer 5 and the retaining disk 7 are bound tightly together. The pad P can tilt for adjustment, owing to the fact that the connector 20 is received in the eye 22 of the arm 25. The pad may be tilted to the desired position by moving the screw 28 in or out, and the pad will be held, by the said screw, in any position to which the pad may have been tilted, an observation which will be understood readily when Fig. 3 is noted. By loosening the screws 30, the pad may be rotated to any position which the operator may select.

It is to be observed that by loosening the screws 55

17, the parts 11 of the back plate B may be moved in or out, thereby adapting the back plate to receive and hold securely, truss pads of different sizes.

5. What is claimed is:

1. A back plate for a truss pad, comprising stiff, plate-like pad-engaging parts disposed approximately in the same plane and laterally adjustable to accommodate pads of different sizes, and 10 mechanism for holding said parts in adjusted, pad-engaging positions, said mechanism embodying transversely spaced members extended across the inner edges of the pad-engaging parts, and means for joining the end portions of each 15 of said members to the respective pad-engaging parts.

2. A back plate for a truss pad, said back plate comprising pad-engaging parts which are laterally adjustable to accommodate pads of different 20 sizes, and mechanism for holding said parts in adjusted, pad-engaging positions, said mechanism comprising a link, means for securing the link to one part of the back plate, and clamping means connecting the link to another of said 25 parts of the back plate, the link having an elongated slot receiving the clamping means slidably, to permit said parts of the back plate to be adjusted toward and away from each other.

3. A back plate for a truss pad, said back plate 30 comprising pad-engaging parts which are laterally adjustable to accommodate pads of different sizes, and mechanism for holding said parts in adjusted, pad-engaging positions, said mechanism comprising a link and a clamping means 35 connecting the link to each of said parts of the back plate, the link being movable longitudinally with respect to each clamping means when both clamping means are loosened.

4. A back plate for a truss pad, said back plate 40 comprising pad-engaging parts which are laterally adjustable to accommodate pads of different sizes, and mechanism for holding said parts in adjusted, pad-engaging positions, said mechanism comprising a link having an elongated slot, and 45 clamp screws in the slot and connecting the link with said parts of the back plate, the slot being longer than the distance between the clamp screw.

5. A back plate for a truss pad, said back plate 50 comprising pad-engaging parts which are laterally adjustable to accommodate pads of different sizes, and mechanism for holding said parts in adjusted, pad-engaging positions, said mechanism comprising a link having a slot, means for securing 55 the link to one part of the back plate, and clamping means in the slot and engaging another part of the back plate, the slot being long enough to permit adjustment of said parts of the back plate toward and away from each other.

60 6. In a device of the class described, a truss pad comprising a base, an inner retainer and an

outer retainer between which the base is gripped, spaced tightening devices joining the retainers, a connector engaged by the tightening devices and held thereby in binding relation to the outer retainer, and an arm mounted on the connector, the outer retainer being a washer having an opening, the connector extending across the opening and having eyes overlapped on the washer, the tightening devices passing through the eyes. 5

7. In a device of the class described, a truss 10 pad comprising a base, an inner retainer and an outer retainer between which the base is gripped, spaced tightening devices joining the retainers, a connector engaged by the tightening devices and held thereby in binding relation to the outer 15 retainer, and an arm mounted on the connector, the outer retainer being a washer having an opening, the connector extending across the opening, and having eyes overlapped on the washer, the tightening devices passing through the eyes, 20 and an adjusting device movably mounted in the arm and engaging the pad, in spaced relation to the connector. 25

8. A device of the class described comprising a truss pad including a base having an opening, a single inner washer engaging the inner surface of the base and having a single opening of approximately the same size as the opening in the base, an outer washer cooperating with the outer surface of the base and having a single opening of approximately the same size as the opening in the base, a retaining disk having a projecting hub defining a flange engaging the inner surface of the inner washer, the hub fitting closely in the opening of the inner washer, clamping devices passing through the opening of the outer washer and of the base close to the peripheries of said openings, the clamping devices engaging the hub of the retaining disk, a rod like connector bridging the opening in the outer washer and having eyes receiving the clamping devices and bound thereby against the outer surface of the outer washer, and an arm mounted to swing on the connector, between the clamping devices. 30 35 40 45

9. In a device of the class described, a truss 50 pad having internal anchorage means and provided with a base having an opening, a washer cooperating with the outer surface of the base and having an opening, a rod like connector extended across the opening of the washer and having eyes overlapped upon the outer surface of the washer, the clamping devices being engaged with the anchorage means, and with the eyes, the clamping devices passing through the opening of the washer and the opening of the base, said 55 openings being of such size as to permit the pad to be adjusted by axial rotation when the clamping devices are loosened, and means mounted on the connector, between the eyes, for joining the pad to the body-engaging member of a truss. 60
